UNITED STATES PATENT OFFICE.

LUCIEN GERVAIS GODET, OF VINCENNES, FRANCE.

DECANTER FOR COOLING LIQUIDS.

SPECIFICATION forming part of Letters Patent No. 544,219, dated August 6, 1895.

Application filed February 20, 1895. Serial No. 539,112. (No model.) Patented in France May 27, 1890, No. 205,895.

To all whom it may concern:

Be it known that I, LUCIEN GERVAIS GODET, engineer, a citizen of the Republic of France, residing at 49 Rue de Lagny, in Vincennes, 5 Seine, France, have invented a certain new and useful Improvement in Decanters for Containing Refrigerated Beverages, (for which I have obtained Letters Patent of France, No. 205,895, dated May 27, 1890;) and I do hereby 10 declare that the following is a full, clear, and exact description of the same, which will enable others skilled in the art to make and use the said invention.

My invention relates to an improved decanter for refrigerated beverages; and it consists in the construction and combination of parts, as hereinafter claimed.

In order that my improvement may be clearly understood and readily carried into 20 effect, I will proceed to describe the same in detail in reference to the accompanying drawing, showing my improved decanter, the plug at the bottom for enabling the introduction of ice not being in section.

25 The decanter is composed of an ordinary main body *r*, which is preferably made of glass, but which might also be made of porcelain, metal, or other suitable material. To the base of the decanter is cemented a ring 30 *s*, made preferably of tin, having a central screw-threaded boss *t*, into which is screwed a metallic plug *u*, the conical part *v* of which fits tightly into the corresponding conical bearing *w*, formed in the boss *t* of the ring.

35 For further safety, the end of the screw-threaded portion *u* can abut at *w* against a second bearing or conical seat formed in the boss *t*. Into the annular groove formed by the boss *t* and the ring *s* fits the lower end of 40 an ice-casing or other ice-vessel *x*, which is closed at the top. A liquid-tight joint between the base of the main body *r*, ring *s*, and

lower end of the vessel *x* is secured by cement *y* or otherwise. The cement for so uniting the isolating vessel *x* to the main body *r* is a 45 compound, which should not be subject to changes, both under the action of intense cold or under the influence of a heat at, say, 120° centigrade.

In using my improved decanter, the plug *u* 50 is unscrewed, the vessel *x* is filled with ice, either in lumps or in a molded block of suitable shape, after which the plug *u* is put into place again and screwed home. The conical portions *v* and *w* being pressed firmly against 55 each other, the ice-vessel becomes liquid-tight, and the jug can then be filled, as usual, with water or other beverage to be cooled for consumption.

It will be readily understood that by the 60 means hereinbefore described while the ice retains its refrigerating power any admixture thereof with the liquid to be consumed is avoided. Furthermore, great economy is 65 gained in the consumption of ice, since it can be preserved longer, owing to its being 70 inclosed and free from the contact of air.

I claim—

A decanter for refrigerated beverages, consisting of a beverage vessel *r*, an independent 70 ice-vessel *x* by which contact with the beverage to be refrigerated is avoided, a ring *s* for connecting the two vessels *r* and *x*, a joint-forming material *y* between *r* and *x*, and a plug *u* screwed into the ring *s*, substantially 75 as described and shown.

In testimony whereof I have hereunto affixed my signature in the presence of two subscribing witnesses.

LUCIEN GERVAIS GODET.
